METHOD AND MEANS FOR MOUNTING SNAP ACTION SWITCH BLADES

Philip C. Jacobs, Jr., Newtonville, Mass., assignor,
by mesne assignments, to The Acro Manufacturing Co., Columbus, Ohio

Application April 13, 1948, Serial No. 20,656

8 Claims. (Cl. 200—67)

1

This invention relates to snap action switches and is particularly concerned with the provision of a mounting for a snap action switch blade which will permit the blade to be mounted and adjusted for a desired operating force in a minimum time and with the required precision.

One of the difficulties in the manufacture of snap action switches has been to make the blades in quantity and still of such uniformity that their operating characteristics will be within the tolerances required. In switch blades of this type the snap action effect is obtained either by stamping the blade in a die to deform a certain critical area of the blade or by drawing the legs of the blade together a certain amount to produce a deformation in the body of the blade similar to that produced by stamping.

However, even under the most carefully controlled conditions, it has been found to be a practical impossibility to produce switch blades in quantity which, when mounted for use in the switches, will have the same operating characteristics. It has therefore been necessary to provide means for making individual adjustments to the switch blades after mounting so that switches of a given type or class will have uniform characteristics. In some instances it is impossible to make these adjustments, in which case the switch must be rejected, thereby raising the cost of the others. Another element contributing to non-uniformity in quantity production is a small variation in the metal from which the blades are made.

In any event, the problem of uniformity in operating characteristics is real and has proved expensive. It is therefore the object of the present invention to provide means for mounting a conventional switch blade of a type now in use in such manner that after mounting it may be adjusted to operate at any desired pressure. It will be understood by those familiar with this art that the more the legs of a switch blade are toed in, the greater will be the required operating force. Therefore, the invention contemplates that the blade will first be mounted in a position where there is little or no toe-in of the legs and thereafter the legs may be progressively toed-in until the proper operating force is attained.

When the legs have reached a position giving the right characteristics to the blade, then the mounting and legs are left in that position, and no further change takes place. The means used for drawing the legs of the switch blade together is of a simple character, but nevertheless

2

less lends itself to great precision. Furthermore, the adjustment may be accomplished rapidly and at low cost, and blades which otherwise would give widely varying operating characteristics may be used in a line of switches with a uniformity that would otherwise be impossible.

The nature of the invention will be more clearly understood as the description proceeds with the aid of the accompanying drawings, in which 10 Fig. 1 is a vertical cross-section of a switch utilizing the mounting means of the present invention.

Fig. 2 is a plan view of the switch mechanism shown in Fig. 1 with the housing cover removed.

15 Fig. 3 is a section on the line 3—3 of Fig. 2 but prior to the adjustment of the blade.

Fig. 4 is a section on the line 4—4 of Fig. 1, showing the mounting after adjustment has been completed.

20 Fig. 5 is an exploded view of the switch blade and mounting means, the assembled parts of which are shown in Fig. 3.

Fig. 6 is a sectional elevation corresponding to Fig. 4, showing a modified form of the invention.

25 Fig. 7 is a vertical cross section on the line 7—7 of Fig. 2, showing a variation in the mounting means for modifying the contact pressures.

Referring to Fig. 1, the snap action switch shown therein comprises a housing having a base 2 and a cover 4. Within this housing are mounted the elements of a snap action switch which consist of a blade 6, a pair of contacts 8 and 10, a mounting support generally referred to at 12 for the fixed end of the blade, and a push button 14 located where it may exert the necessary force on the blade to cause actuation.

The construction of the switch housing, blade and operating means is conventional, the invention residing in the means by which the blade is mounted and the adjusting mechanism that is included therein.

The switch blade 6 is plainly shown in Figs. 2 and 5. When mounted in the manner herein-after described, the movable end contact 16 alternately comes into engagement with contacts 8 and 10 as the blade is actuated. In the present instance the normal position of the switch blade will have contacts 10 and 16 in engagement. When the operating button 14 is pressed downwardly the blade will snap up to an unbalanced position with contact 16 in engagement with contact or stop 8. Thereafter, when push button 14 is released, the blade will return to the stable down position shown in Fig. 1.

55 In the particular blade construction shown

herein, there are a pair of legs 18 and 20 which extend from the blade body to the support 12. A centrally located tongue 22 constitutes the operating lever against which button 14 is pressed. In order that the body of the blade may be suitably arched at the critical area 24, which area reverses itself by snap action upon pressure on tongue 22, it is necessary that legs 18 and 20 be toed-in, as shown in Fig. 2, a greater or less degree. The more these legs are toed-in, the more area 24 will be arched and the more the force required against tongue 22 to cause the blade to snap. It will be noted in Fig. 5 that blade 6 before assembly has legs 18 and 20 in flat untoed-in position, and there is, of course, no arched critical area as yet at 24.

The construction of the mounting support 12 in relation to the legs 18 and 20 constitutes that part of the invention that makes rapid adjustment possible. The base 2 has a projection 26 extending upwardly therefrom shaped as a T. The cross bar 28 is merely a reinforcement for the base and is not concerned with the invention. The legs 18 and 20 are notched at their ends as at 30 and 32 to produce short fingers 34 and 36. The blade 6 is positioned on support 26 with the fingers 34 and 36 overlying in part the short leg 38 of support 26. A spacer 40 similar in shape to support 26 is placed on top of legs 18 and 20 with hole 42 aligned with hole 44 of support 26. A clamp 46 having a pair of partially down-turned clamping members 48 and 50 is then placed on top of spacer 40 and the parts are all secured together in the present instance by the bolt 52 and nut 54, plainly shown in Figs. 1 and 2. It will be understood that other securing means, as a rivet, for example, may be used if preferred. When the nut is set up snugly but not too tight, it will be seen that all of the parts will be arranged as shown in Fig. 3. The outside edges of fingers 34 and 36 are farther apart than the width of the underlying supporting portion 38, while the short tongue 56 of the spacer is likewise of less width than the fingers 34 and 36.

With the parts in this assembled position, the legs 18 and 20 will be without any toe-in, and there will be as yet no snap action characteristic to spring blade 6. A suitable tool is then applied to members 48 and 50, squeezing them together to bring pressure to bear on fingers 34 and 36. This pressure is great enough to overcome the existing clamping force exerted on legs 18 and 20 by spacer 40 under the pressure exerted thereon by clamp 46. Thus the legs 18 and 20 are gradually drawn together, and as this occurs, arching of the critical area 24 commences and the blade develops snap action characteristics. When the toeing-in of the legs has proceeded only a slight distance, then only a very small force will be required against tongue 22 to cause blade actuation. As the legs are drawn together more and more, the force to operate the blade will increase. By suitable scales and other measuring devices it is possible to continue the drawing together of legs 18 and 20 until they reach a point where a desired predetermined force is required against tongue 22 to operate the blade. At this point the squeezing together of members 48 and 50 ceases. The friction under which the legs find themselves at this time is adequate to maintain them in the final set position. Fig. 4 is illustrative of the position members 48 and 50 may assume by the time the required toeing-in has reached completion.

Thus it is seen that a simple and convenient mounting means has been provided whereby a spring blade having no snap action characteristics when initially mounted may be quickly and simply adjusted to give it the characteristics required within any set tolerances.

The object of the inclusion of spacer 40 is to make it possible for the members 48 and 50 to be squeezed against fingers 34 and 36 in a generally horizontal direction. If spacer 40 were omitted, it is apparent that the initial pressure of members 48 and 50 would be less effective to move fingers 34 and 36 toward each other. However, by providing a modified form of clamp, such as is shown in Fig. 6, the spacer may be omitted. Here the clamp 58 has clamping members 58 and 60 which are first turned upwardly as at 62 and 64 before being bent down to blade-engaging position. By this construction the fulcrum about which the members 58 and 60 pivot is raised a considerable distance above fingers 34 and 36 so that the squeezing effect of members 58 and 60 will be more nearly horizontal, the same as was the case with members 48 and 50.

In the construction heretofore described it has been contemplated that the legs 18 and 20 will be clamped initially in the same horizontal plane and that their movement toward each other as adjustment proceeds will likewise be in the same plane.

A blade thus mounted and stressed has a stable position in which contact 16 rests against contact 10 and an unstable position with contact 16 against contact 8 reached after button 14 has been depressed sufficiently to cause blade actuation. The pressure between contacts 16 and 10 in the stable position in normal mounting position is less than the pressure between contacts 16 and 8 in the unstable position. This condition may be undesirable in some instances, and accordingly the invention also includes a modified form of mounting means and blade formation which makes it possible to control or adjust the stable and unstable contact pressures as may be required. The variation may be brought to a point where the stable and unstable contact pressures are substantially equal.

The mounting and blade formation that achieve this result are shown in Fig. 7. The base 2 has a projection or supporting member 70 in general similar to support 26. The upper surface 72, however, instead of being flat, slopes downwardly toward the sides at those areas against which the legs of the blade normally rest. The angle of the slope on each side as at 74 and 76 is substantially equal, so that the angle of twist of the blade legs will be equal and the parts of the blade symmetrical. The clamp 78 corresponds to the clamp 58 shown in Fig. 6. If a spacer is used, the clamp would correspond to clamp 46 shown in Fig. 5. In any event, clamp 78 is so shaped that when it is drawn downwardly to squeeze legs 18 and 20 against support 70 the legs will be twisted slightly, as shown. The clamping action between clamp 74 and support 70 will be spread over both surfaces of the legs 18 and 20 at the flat areas of contact, so that the gripping of the legs will be just as secure as in the forms heretofore described.

After the legs have been gripped in this twisted condition, the inwardly operating force is then applied to the leg extensions, so that the two legs, while being brought together, slide upwardly

along the inclined surfaces 74 and 76 until the desired operating characteristics are reached.

The effect of this construction is to cause the contacts in stable position to exert a greater pressure on each other and the contacts in unstable position to exert a less pressure on each other. The degree of the slopes of 74 and 76 combined with the extent the legs are thereafter drawn together controls the stress in the blade and the resulting stable and unstable position pressures. The construction therefore provides a ready and convenient means for not only achieving uniform operating characteristics in switches produced in quantity, but also permits varying of the relative contact pressures through the simple expedient of providing supporting blocks 10 having upper surfaces of varying slopes.

In general it is preferred that slopes 74 and 76 be equal, so that the twist in the blade legs will be equal and symmetrical. Clamp 78 is formed to have an overall angularity that will be somewhat more acute than the angularity between faces 74 and 76, so that as the clamp is drawn down against the top of the blade legs it will flex slightly until the compressive force is applied generally over the entire overlapping areas.

While preferred forms of the invention have been shown and described, it is to be understood that the invention is not to be limited thereby but only by the appended claims.

I claim:

1. A mounting for a snap action switch blade having a pair of legs which must be toed in to give the desired operative effect, said mounting comprising a base, a support on said base of sufficient width to engage the under flat areas of the ends of said legs when said blade is placed thereon, a clamp adapted to overlie the upper surfaces of the ends of said legs, said clamp having a pair of oppositely disposed downturned members integral with said clamp for engaging the outer edges of the ends of said legs, and means for drawing said clamp toward said support whereby said legs may be clamped therebetween and said downturned members will be in a position to engage and move said leg ends toward each other.

2. A mounting for a snap action switch blade having a pair of legs which must be toed in to give the desired operative effect, said mounting comprising a base, a support on said base of sufficient width to engage the under flat areas of the ends of said legs when said blade is placed thereon, a clamp adapted to overlie the upper surfaces of the ends of said legs, said clamp having a pair of oppositely disposed downturned members integral with said clamp for engaging the outer edges of the ends of said legs, a portion of each of said members adjacent the body of said clamp being bent upwardly above the top surface of said clamp, and means for drawing said clamp toward said support whereby said legs may be clamped therebetween and said downturned members will be in a position to engage and move said leg ends toward each other.

3. A snap action switch comprising a base, a support on said base, said support being of non-uniform width, a snap action switch blade having a pair of legs which must be drawn together to give the required snap action characteristics to said blade, said legs positioned on said support and frictionally maintained in said position by a spacer blade positioned on the upper surface of the ends of said legs, a clamp above and rest-

ing on said spacer, means for compressively holding the parts together to secure said legs firmly in position, the outer edges of the ends of said legs when in unstressed position being farther apart than the width of that part of the support which they overlie, downturned members integral with said clamp positioned where they may engage the said outer edges of said legs whereby, upon the application of a superior force to said members, said members may be bent toward each other to engage and move said legs toward each other until the desired operating characteristic of the switch blade has been obtained.

4. The combination of a mounting and a snap action switch blade having a pair of legs which must be toed in to produce the desired operative effect, said mounting comprising a clamp having two non-parallel engaging surfaces sloping toward each other for frictionally gripping said legs on their opposed surfaces and at a symmetrical angle to each other, so that said legs when gripped at their ends are slightly twisted, a portion of each of said legs extending beyond said clamping means, and means constituting part of said clamping means by which a compressive force may be transmitted simultaneously to the said ends of the said legs in the direction of the plane of each clamped end of said blade, whereby when said force is sufficient to overcome the said clamping force, said legs may be moved toward each other while still being gripped by said clamp.

5. A snap action switch comprising a base, a support on said base, a clamp above said support, means for drawing said clamp and support together, a snap action switch blade having a pair of legs, said legs being positioned between said support and said clamp, the areas on said support and said clamp in contact with one of said legs being at an angle to the areas on said support and said clamp that are in contact with the other of said legs, means for applying sufficient clamping force to said support and clamp to maintain said legs wherever they may be set with respect to said clamp, said legs extending beyond the said clamping areas to provide portions which may be engaged by means of sufficient strength to move said legs toward each other by overcoming the gripping force of said clamp.

6. The method of adjusting a snap action blade of the type having legs that must be toed-in to give the required characteristics, said method comprising the steps of clamping said legs in symmetrical twisted positions with the clamped portions lying in non-parallel planes, applying to each leg at its outer edge near the end thereof a force in the direction of the plane of each clamped leg, said force being of sufficient degree to overcome said clamping force whereby toeing-in of said legs is progressively accomplished, testing for operating characteristics as the toeing-in of said legs progresses and thereafter, when the required characteristics have been reached, holding said legs with sufficient restraining force to prevent their subsequent displacement during normal use.

7. A mounting for a snap action switch blade of the type having a pair of legs which must be toed-in to give the desired operative effect, said mounting comprising a base, a support on said base having spaced non-parallel areas sloping toward each other, said non-parallel areas positioned to engage the under flat areas of the ends of said legs when said blade is placed thereon, a

clamp adapted to overlie the upper surfaces of the ends of said legs, said clamp having its under surface shaped to force said legs against said non-parallel areas thereby clamping and simultaneously twisting the ends of said legs in opposite directions, said clamp having a pair of oppositely disposed downturned members integral with said clamp for engaging the outer edges of the ends of said legs, and means for drawing said clamp toward said support whereby said legs may be clamped therebetween and said downturned members will be in a position to engage and move said leg ends toward each other.

8. A snap action switch comprising a base, a switch blade having a pair of legs, non-parallel frictional gripping surfaces connected to said base and sloping toward each other and constituting means for gripping said legs initially in a twisted non-toed-in condition and permitting sliding movement of said legs toward each other upon the application of a superior inward force to the ends of said legs, said gripping surfaces thereafter maintaining said legs in a position where

5 said legs are oppositely twisted and toed-in toward each other to produce a blade with snap action characteristics, a contact on a movable part of said blade and a contact on said base 10 position for stable and separable engagement with said blade contact, said twisting and toeing-in of said legs producing a greater pressure between said contacts in stable position for the amount of toed-in movement than would be obtained with the legs in untwisted condition.
